United States Patent Office.

AUGUSTIN THOMA, SR., OF PIQUA, OHIO.

Letters Patent No. 70,049, dated October 22, 1867.

IMPROVEMENT IN TOOLS FOR JEWELLING WATCHES.

The Schedule referred to in these Letters Patent and making part of the same.

TO ALL WHOM IT MAY CONCERN:

Be it known that I, AUGUSTIN THOMA, Sr., of Piqua, in the county of Miami, and State of Ohio, have invented a new and useful Improvement in Jewelling Watches; and I do hereby declare that the following is a full, clear, and exact description thereof, which will enable others skilled in the art to make and use the same, reference being had to the accompanying drawings, forming part of this specification, in which—

Figure 1 is a sectional view of a watch-plate with a jewel inserted in it, showing the application of the tool employed for closing the bezel and setting the jewel.

Figure 2 is a view of the tool in its handle.

Similar letters of reference indicate like parts.

This invention relates to setting jewels in watch-plates with a tool which raises and closes back the bezel or burr for securing the jewel in the plate at a single operation with great dispatch and accuracy, instead of using the ordinary pointed burnishing-tool, which requires time and skill to make a good setting.

A represents part of a watch-plate, and α a jewel, fitted in the larger end of a taper-hole in the plate in the usual way for setting jewels. B represents the tool employed for raising and closing back upon the jewel the bezel or burr to hold it in place. The tool is a round, hardened steel, cup-shaped point, c , the edge or rim around the cup or concave opening in the end being made very sharp for the purpose of cutting into the metal around the jewel, and raising a delicate burr or bezel, which is done by placing the cup c over the jewel α in the plate A, and turning it around in opposite directions with a gentle pressure. The bezel thus raised is closed back over the jewel by the conical sides of the cup c bearing upon it at the same operation. The tool is made of various sizes to fit jewels of different sizes, and the sharp edge or rim extends outside of the jewel for which it is used just enough to raise and secure a delicate bezel around it. One handle, C, is used for any number of different-sized tools, which all fit in a socket, d , as shown in fig. 2.

By means of this tool watches are jewelled with much greater facility and accuracy than by the old method.

Having thus described my invention, what I claim as new, and desire to secure by Letters Patent, is—

The tool B for closing or setting jewels in watch-plates, consisting of the round, hardened, cup-shaped point c , substantially, as herein shown and described.

The above specification of my invention signed by me this 17th day of August, 1866.
